UNITED STATES PATENT OFFICE.

NAZZERENO TOGNACCI, OF KINCAID, ILLINOIS.

SHIP-RAISING DEVICE.

1,302,245.

Specification of Letters Patent. Patented Apr. 29, 1919.

Application filed March 4, 1918. Serial No. 220,319.

To all whom it may concern:

Be it known that I, NAZZERENO TOGNACCI, a subject of the King of Italy, residing at Kincaid, in the county of Christian and State of Illinois, have invented certain new and useful Improvements in Ship-Raising Devices, of which the following is a specification.

The primary object of the invention is the provision of a device adapted for raising sunken vessels to the surface of the water easily and quickly, the device possessing great strength and being simple in construction.

15 A further object of the invention is to provide a pneumatic means for raising sunken vessels and providing an arrangement for changing weighted members attached to the vessel into elevating floats 20 therefor, the device being readily operable from the surface of the water in the neighborhood of the vessel to be raised.

With these general objects in view and others that will appear as the nature of the 25 invention is better understood, the same consists in the novel construction, combination and arrangement of parts hereinafter more fully described, illustrated in the accompanying drawings, and then claimed.

30 In the drawings forming a part of this application and in which like designating characters refer to corresponding parts throughout the several views,

Figure 1 is an elevational view of the 35 device illustrated in its operative arrangement in raising a sunken vessel.

Fig. 2 is a sectional view of one of the 40 floats having an attaching chain with a vessel indicated by dotted lines supported by the chain.

Fig. 3 is a similar view of one of the floats during the inflation thereof.

Fig. 4 is a transverse sectional view of a 45 float taken upon line IV—IV of Fig. 3 and

Fig. 5 is a diagrammatical view of the operating pump and piping employed with the floats.

Referring more in detail to the drawings, a sunken vessel 10 is herein illustrated resting upon the bottom 11 of the ocean 12 while a ship 13 upon the surface of the water is provided with my device by means of which the vessel 10 may be easily raised to a point alongside of the ship 13.

55 A plurality of hollow globular preferably metal floats 14 are provided, substantially

pear-shaped as herein shown having an inlet head 15 at one end and a valve casing 16 at its opposite end for accommodating an outlet valve 17. This valve is normally closed 60 by means of the water pressure when the float 14 is submerged while a handle 18 is provided for the said valve 17 for opening the same when desired.

Oppositely arranged hooks 19 are provided upon the head 15 with the opposite ends of a chain 20 positioned upon said hooks, thereby forming a chain loop adapted for positioning around the vessel 10 for raising the same. A weight 21 is preferably 65 provided for each of the chains 20 and it will be understood that divers will be employed for positioning the chains 20 around the vessel 10 and then attaching the chains to the hooks 19 of the floats 14, the said floats 70 being adapted to be filled with water for sinking the floats to a point adjacent the deck of the submerged vessel.

With the water filled floats 14 connected to the vessel 10 in the manner described, a 75 combined elevating water pump and air compressor 22 which is arranged at any convenient point upon the ship 13 is employed for pumping the water out of the floats 14 and forcing air into the floats for taking the 80 place of such water.

The valve casings 16 are connected to the water pumping side 23 of the pump 22 by means of suitable pipes 24 while the inlet heads of the floats 14 are connected to the 85 air compressing side 25 of the pump 22 by means of suitable hose 26.

With the device arranged as shown in Fig. 1 of the drawings, it will be understood that by operating the pump 22, the water 27 90 within the floats 14 will be extracted therefrom through the pipes 24 while air will be pumped into the floats 14 through the bottom heads 15 by the use of the hose 26. A funnel or injector tube 28 is carried by the valve 95 casing 16 of each float 14 and axially positioned within the float for assisting the cooperative action of the incoming air of the hose 26 as well as the pumping suction within the pipes 24 to quickly supplant the water 100 27 within the floats with compressed air for causing the floats to rise, thereby carrying the vessel 10 upwardly through the water.

It will be understood that the pump 22 may be of any desired form it being only essential that the water is pumped outwardly 110 from the floats 14 through the pipes 24

simultaneously with the flow of air into the floats through the hose 26. A serviceable device for quickly raising sunken vessels is provided which requires only a few workmen 5 and divers and has but few parts and these are only slightly liable to injury.

What I claim as new is:—

1. A device of the class described comprising a hollow vertical float, an inlet head at 10 the lower end of the float, a vessel engaging chain suspended from said head, air supplying hose attached to said head, and a water exhausting pipe connected to the upper end of the float.
- 15 2. A device of the class described comprising a hollow vertical float, an inlet head at the lower end of the float, a vessel engaging chain suspended from said head, air supplying hose attached to said head, a water exhausting pipe connected to the upper end of the float, an injector tube within the float between the air inlet and water outlet ends thereof, and a combined water pump and air compressor arranged at a distance from the 20 float operatively connected to said pipe and said hose.
- 25 3. A vessel raising float comprising a substantially pear-shaped vertical hollow body,

an inlet head at the lower end of the body, chain suspending means carried by said head, an air supplying hose connected to said head, a valve casing at the upper end of the body, a water exhaust pipe attached to said casing, a valve within the said casing, and a funnel-shaped member axially arranged 30 within the body secured to said casing at the smaller end and with its open larger end positioned adjacent said head.

4. A vessel raising float comprising a substantially pear-shaped vertical hollow body, 40 an inlet head at the lower end of the body, an air supplying hose connected to said head, a valve casing at the upper end of the body, a water exhaust pipe attached to said casing, a valve within the said casing, a funnel-shaped member axially arranged within the body secured to said casing at the smaller 45 end and with its open larger end positioned adjacent said head, a vessel engaging chain detachably suspended from said head, a weight carried by said chain, and a combined water pump and air compressor operatively connected to the said hose and said pipe.

In testimony whereof I affix my signature.

NAZZERENO TOGNACCI.
